US0D1059113S

(12) **United States Design Patent** (10) Patent No.: **US D1,059,113 S**
(45) Date of Patent: ** Jan. 28, 2025

(54) **COOLER**

- (71) Applicant: **PepsiCo, Inc.**, Purchase, NY (US)
- (72) Inventors: **Michel Alvarez**, Miami, FL (US); **Xavier Cortadellas**, Hallandale Beach, FL (US); **Sean Joseph Huls**, Chicago, IL (US); **William Owen Stock**, Chicago, IL (US); **Matthew K. Lider**, North Bend, WA (US); **Yang Ouyang**, Sammamish, WA (US); **David Robert Schlesinger**, Seattle, WA (US); **Joshua Stough**, Kirkland, WA (US); **Sarah White**, Redmond, WA (US)
- (73) Assignee: **PepsiCo, Inc.**, Purchase, NY (US)
- (**) Term: **15 Years**
- (21) Appl. No.: **29/937,129**
- (22) Filed: **Apr. 12, 2024**
